LENS STRAP STRUCTURE

Bert J. Lowres, East Orange, N. J.

Application September 10, 1938, Serial No. 229,288

2 Claims. (Cl. 88—47)

This invention relates to improvements in lens strap connections for ophthalmic mountings; and the invention has reference, more particularly, to a novel strap structure for supporting lenses in connection with various desired elements of a rimless ophthalmic mounting, as e. g. in connection with the center piece or bridge, nose guards, temple pivoting end pieces, etc.

This invention has for its objects to provide a novel lens strap structure which is self-adjusting to any thickness of lens; which locks securely against loosening when secured to the lens; and which is of neat and attractive appearance, being provided with a fastening screw means having a slotless head which countersinks flush to the face of the external strap plate when in place, and which is thus subject to being engraved in conjunction with said strap plate face so as to be indiscernible.

Other objects of this invention, not at this time more particularly enumerated, will be understood from the following detailed description of the same.

Fig. 1 is a fragmentary front face view of an ophthalmic mounting and lens equipped with the novel lens strap structure according to this invention; Fig. 2 is a rear face view of the same; Fig. 3 is a top edge view of the lens strap structure drawn on an enlarged scale; Fig. 4 is a longitudinal horizontal section assembled, and Fig. 5 is a similar section disassembled; Fig. 6 is an exterior face view of the front plate of the strap structure; and Fig. 7 is an interior face view of the rear plate of the strap structure.

Similar characters of reference are employed in the above described views, to indicate corresponding parts.

Referring to the drawing, the reference character 10 indicates the front plate of the strap structure, the same having integrally formed at one end thereof an angular butt portion 11 adapted to extend across the edge of a lens L to which the strap structure is to be applied. Extending in opposite directions respectively from the upper and under sides of said butt portion 11 are arcuate strap portions 12 adapted to engage the adjustment edge of the lens L. A desired element of a rimless ophthalmic mounting is suitably secured to the butt portion 11. In illustration of this, there is shown in Fig. 1, a center piece or bridge 13 so secured to said butt portion 11, but it will be understood that other elements such as nose guards, temple end pieces, etc., may, when desired, be connected with the strap struc-

ture of this invention in like or in any other suitable manner.

The front plate of the strap structure 10 is provided with a suitably shaped perforation or opening for operative alignment with an opening 14 with which the lens L is provided, to receive therethrough a suitable screw-threaded fastening stud 15. This fastening stud 15 is provided with a head 16 having a male interlocking portion 17 of square or other selected polygonal cross sectional shape, and said head is further provided outwardly of said interlocking portion 17 with a circular head piece 18. The perforation provided in the front plate 10 is shaped to conform to the head 16 of said fastening stud 15, and so that said head 16 countersinks therein flush with the external face surface of said front plate 10. Illustrative of this said front plate perforation comprises an inner square socket 19 to correspond to and receive said square interlocking portion 17 of the stud 15, and an outer circular socket 20 to correspond to and receive the circular head piece 18 of the stud, whereby said stud, when operatively assembled with the front plate 10 is interlocked therewith against relative rotation, while at the same time the head is countersunk flush with the external face surface of the front plate 10. This latter arrangement substantially conceals the stud 15, especially when the external face of the front plate 10 is engraved, and consequently permits of a very neat and attractive appearance of the obverse side of the strap structure when the latter is operatively incorporated in an ophthalmic mounting.

The reference character 21 indicates the rear plate of the strap structure. This rear plate is a separable element of the strap structure, and is provided with a notched rearward end portion, the notch 22 of which constitutes a female coupling element adapted to cooperate with a laterally projecting lug 23 with which the butt portion 11 of the front plate 10 is provided, said lug 23 constituting the cooperative male coupling element.

Rotatably mounted in connection with the body 45 of said rear plate 21 is a nut member comprising a journal portion 24 having an outer annular keeper flange 25. Said journal portion 24 is rotatably supported in a bearing opening 26 with which the rear plate 21 is provided, said bearing opening having a diametrically enlarged outer portion 27 to receive said keeper flange 25, thus forming a shoulder 28 engaged by said flange 25 so that inward axial displacement of said nut member is prevented. The inner face 55

of said rear plate 21 is formed with a countersunk chamber 29. The inner end of said journal portion 24 is beaded over within said chamber 29 to provide a second keeper flange 30 bearing against 5 the bottom of said chamber 29 so that outward axial displacement of said nut member is prevented. At its outer end said nut member is provided with a head 31 of square or other selected polygonal shape. The nut member is provided with an internally screw-threaded axial bore 32. It will be obvious that the nut member has a permanent swiveled relation to said rear plate 21.

In applying the novel strap structure to a lens 15 L, the front plate 10 is applied over the front face of said lens, with the arcuate strap portions 12 abutting the lens edge. As thus disposed the perforation or opening of the front plate will align itself with the opening 14 of the lens L, whereupon 20 the stud 15 is inserted through these parts with its head 16 countersunk in the body of said front plate as above described. The rear plate 21 is thereupon opposed to the rear face of the lens L and its nut member aligned with the stud 15, 25 whereupon said swiveling nut member is rotated, by means of a suitable wrench tool (not shown), to cause the same to screw over and down upon said stud 15, thus drawing down upon the rear face of the lens L said rear plate 21. As the rear 30 plate 21 is thus tightened home, its notched end 22 will move into straddling relation to the lug 23 carried by the front plate butt, and will thus interlock with the latter so as to be retained aligned with the front plate 10 and against rotative displacement.

It will be obvious that a very simple, easily manipulated and applied strap structure is provided by this invention, whereby, owing to the bodily movement relative to the front plate 10 40 of which the rear plate 21 is capable, the said strap structure is self adjusting to various thicknesses of lenses, and wherein, when applied to a lens, the strap plates will respectively engage flatly against the lens faces without setting up 45 unequal pressures or stresses in lens, and consequently eliminating risk of lens fracture due to such causes.

In addition to its mechanical advantages, the novel lens strap structure is such that its obverse 50 side is free from unsightly projecting screw heads or like protuberances, the same presenting a smooth face which may be decoratively engraved, thus concealing even the lines of joint between the same and the stud head 16.

Having thus described my invention, I claim:

1. A lens strap structure for ophthalmic mountings comprising, a front plate and a rear plate between which a lens is receivable, a non-rotatable screw-threaded stud to extend through an engaged lens from said front plate, said rear plate having a chambered inner face, said rear plate also having a bearing opening leading outwardly from said chambered inner face thereof and provided with a diametrically enlarged outer portion, a swivel nut member carried by said rear plate to engage said stud, said nut member having a journal portion mounted in said bearing opening and a keeper flange seated in the enlarged outer end portion of the latter, the inner end of said journal portion having a second keeper flange disposed in the chambered inner face of said rear plate, and the outer end of said nut member having a squared head projecting beyond the outer face of said rear plate. 20

2. A lens strap structure for ophthalmic mountings comprising, a front plate having lens edge abutting means at one end thereof, a screw-threaded stud to extend through an engaged lens from said front plate, said stud having a head countersunk in said front plate flush with the outer face thereof, cooperative means on said stud head and front plate for interlocking the stud and front plate against relative rotation, a separable rear plate having a chambered inner face, said rear plate having a bearing opening leading outwardly from said chambered inner face thereof and provided with a diametrically enlarged outer end portion, a swivel nut member carried by said rear plate to engage said stud, said nut member having a journal portion mounted in said bearing opening and a keeper flange seated in the enlarged outer end portion of the latter, the inner end of said journal portion having a second keeper flange disposed in the chambered inner face of said rear plate, the outer end of said nut member having a squared head projecting beyond the outer face of said rear plate, a laterally projecting lug extending rearwardly from the lens and abutting means of 30 said front plate, and said rear plate having a notched end portion to straddle said lug to thereby retain said rear plate against rotative displacement when assembled with said front plate and a served lens. 40
